UNITED STATES PATENT OFFICE.

CHARLES R. HILTY, OF CHICAGO, ILLINOIS.

ROTARY COMPOUND STEAM-ENGINE.

957,508.

Specification of Letters Patent. Patented May 10, 1910.

Application filed December 13, 1909. Serial No. 532,958.

To all whom it may concern:

Be it known that I, CHARLES R. HILTY, a citizen of the United States, residing at Chicago, county of Cook, and State of Illinois, 5 have invented certain new and useful Improvements in Rotary Compound Steam-Engines, of which the following is a specification.

My invention relates to improvements in 10 rotary compound steam engines and has for its object the production of an engine of this character that shall be compact and symmetrical in design and efficient in operation.

15 A further object of my invention is to provide means incorporated in the throttle valve of the engine for controlling the flow of steam to the high and low pressure cylinders, and a further object is to provide suitable means for reversing the engine. Other 20 objects will appear hereinafter.

With these objects in view my invention consists in the novel construction and arrangement of parts which will be herein- 25 after fully described and more particularly pointed out in the appended claims.

30 My invention will be best understood by reference to the accompanying drawings forming a part of this specification, and in which,

Figure 1 is a vertical section of my improved engine taken on line $x-x$ of Fig. 3, Fig. 2 is an end elevation thereof, Fig. 3 is a vertical longitudinal section taken on line 35 $y-y$ of Fig. 1, Fig. 4 is a vertical section of an improved compound throttle valve provided for the engine, Fig. 5 is an end view thereof, and Fig. 6 is a central vertical section.

40 Referring now to the drawings, 1 designates the engine casing and 2 a power shaft journaled therein by means of roller bearings as shown. Fixed to the shaft 2 and adapted to rotate in the casing 1 is a cylindrical piston 3 having two diametrically opposed radial blades which are provided with longitudinal packing strips as shown. Rotatable cylindrical members 4 which serve the function of cylinder heads are mounted 45 diametrically opposite in the casing 1 and are each in contact with the periphery of the piston 3 or the packing strips provided therefor. The oppositely disposed high pressure annular steam expansion chambers 50 or cylinders 5 and 6, the piston 3, and the members 4 are similar in every respect to

corresponding members of the low pressure cylinders, the latter, however, having a greater length and volume than the high pressure cylinders. The piston 3' of the 60 low pressure cylinder is fixed to the power shaft 2, and the other parts have the same relation thereto as is shown in the high pressure cylinder. A drive spur gear 7 is fixed to one end of the power shaft 2, and geared 65 therewith are gears 8 which are fixed to and are adapted to rotate the shafts or journals 9 to which the members 4 are secured, the ratio of said gears being 2:1 as clearly shown in Fig. 2. The diameter of piston 70 3 is double that of the members 4, and these members having a rolling contact on said piston, the friction and consequent wear due to sliding friction being thus obviated. The peripheral recess 10 provided in each member 4 is adapted to register with a blade of a piston and to permit the same to pass said member in its rotation with the power shaft 2. Packing strips are provided to prevent 75 leakage past the members 4.

80 The valve mechanism for the high and low pressure cylinders are similar and comprise rocker valves 12 which are properly mounted and timed to control the admission and exhaust of the engine. Pipes 13 and 14 85 connected to the high pressure cylinders serve as admission and exhaust pipes respectively when the engine is running in the direction indicated, and pipes 13' and 14' respectively serve as admission and exhaust 90 pipes for the low pressure cylinders.

95 The valves 12 are rocked simultaneously by means of the valve gear shown in Figs. 2 and 3. This gear comprises two oppositely disposed eccentrics 17 which are secured to each end of a shaft 9, said eccentrics being provided with eccentric rods 19. These eccentric rods are pivoted to the opposed ends of a link 21 which is arranged to slide over a pin 22, the latter being secured in the face 100 of an oscillatory disk 23. The link 21 is pivoted to an operating rod 24 which may be moved by hand or by other suitable means and adapted to hold said link in the position relative to the eccentric rods as 105 shown in Fig. 2 when the engine is running as indicated. The free end of the rod 24 may be locked in position by suitable means (not shown), and to reverse the engine said rod is moved over so that the pin 22 is in 110 the other end of the link 21. Thus one end of the link 21 is always free to move ver-

tically by means of the eccentric rod connected thereto, and the other end of the link oscillates the disk 23 through the medium of the pin 22. Each rocker valve 12 is provided with an arm 25 at its outer end, and parallel rods 26 connect these arms, the rods 27 leading to and being moved by the oscillatory disk 23.

The compound throttle valve 28 comprises chambers or cylinders 29 and 30 having oscillatory valves 30' mounted therein. Each valve is provided with an outwardly projecting stem 31 to one of which an arm 32 is secured and to the other a throttle wheel 33, said arm and throttle wheel being connected by means of a parallel rod 34. Thus when the throttle wheel is rotated by hand the valves move simultaneously and open or close their respective ports. In Fig. 4 the movement of the valves is illustrated, the full line position showing the position required when the engine is running in the direction indicated.

The engine operates as follows: When the valves are turned from the intermediate dotted line position to the full line position the eccentrics are in the position shown, steam will flow into the admission pipes 13 and thence through the high pressure cylinders. Then after the piston blades pass the exhaust ports the steam passes through the exhaust rocker valves into the exhaust pipes 14 and thence into the respective chambers 35 and 36 having the port 37 therebetween. The steam then flows through the pipes 13' to the low pressure cylinders and thence through the pipes 14' to the chamber 38 whence it passes to atmosphere through the pipe 39. To reverse the engine the link 21 is thrown over as aforesaid and the throttle valve turned so that the valves will be in the other extreme or dotted line position which causes the admission pipes to then serve as exhaust pipes.

It will be noted that the parts are arranged in perfect balance and that consequently a minimum of vibration is produced during the operation of the engine.

While I have shown what I deem to be the preferable form of my invention I do not wish to be limited thereto as there might be various changes made in the details of construction and the arrangement of parts described without departing from my invention, and hence I desire to avail myself of such changes and alterations as fairly fall within the spirit and scope of the appended claims.

Having described my invention what I claim as new and desire to secure by Letters Patent is:

1. In a rotary engine, a casing provided with an annular expansion chamber, a power shaft rotatably mounted in said casing, a cylindrical piston mounted in said power shaft

and forming the inner wall of said annular chamber, diametrically disposed piston blades on said piston and traveling in said annular chamber, diametrically opposed cylindrical members in rolling contact with said piston and provided with recesses adapted to permit the passage of said piston blades, admission and exhaust ports for said chamber, means for opening and closing said ports to effect the continuous rotation of said piston, and means for rotating said cylindrical members, said last named means comprising spur gears secured to the journals of said members in mesh with a gear secured to said power shaft, and said first named means comprising rocker valves mounted in said casing and adapted to operate simultaneously substantially as described.

2. In a rotary engine, a casing provided with an annular expansion chamber, a power shaft mounted in said casing, a cylindrical piston mounted on said power shaft and forming the inner wall of said annular chamber, diametrically disposed piston blades on said piston and traveling in said annular chamber, diametrically opposed cylindrical members in rolling contact with said piston and provided with recesses adapted to permit the passage of said piston blades, admission and exhaust ports for said chamber, means for opening and closing said ports comprising rocker valves mounted in said casing having arms at their outer ends, parallel rods connecting said arms, an oscillatory disk mounted on said casing connected with and adapted to actuate said valve arms, and means for oscillating said disk, substantially as described.

3. In a rotary engine, a casing provided with an annular expansion chamber, a power shaft rotatably mounted in said casing, a cylindrical piston mounted on said power shaft and forming the inner wall of said annular chamber, diametrically disposed piston blades on said piston and traveling in said annular chamber, diametrically opposed cylindrical members in rolling contact with said piston and provided with recesses adapted to permit the passage of said piston blades, admission and exhaust ports for said chamber, means for opening and closing said ports comprising rocker valves mounted in said casing having arms at their outer ends, parallel rods connecting said arms, an oscillatory disk mounted on said casing connected with and adapted to actuate said valve arms, a pin secured in the face of said disk, a link adapted to slide on said pin, eccentric rods pivoted to said link at each extremity thereof, and oppositely arranged eccentrics secured to a journal of one of said cylindrical rotatable members for actuating said eccentric rods, substantially as described.

4. In a compound rotary steam engine, a casing provided with adjacent high and low

pressure annular expansion chambers; a power shaft rotatably mounted in said casings; cylindrical pistons mounted on said power shaft and forming the inner walls of 5 said annular chambers; diametrically disposed piston blades on said pistons and traveling in said annular chambers; diametrically opposed cylindrical members in rolling contact with said pistons and provided with 10 recesses adapted to permit the passage of said piston blades, admission and exhaust ports for said chambers; means for opening and closing said ports to effect the continuous rotation of said pistons; and a compound

throttle valve having two cylindrical chambers in which oscillatory valves are mounted and adapted to control the flow of steam to and from the engine cylinders which are tied to said throttle valve, substantially as described. 15

In testimony whereof I have signed my name to this specification in the presence of two subscribing witnesses. 20
